UNITED STATES PATENT OFFICE.

JOHN M. HOLLADAY, OF HOLLADAY, VIRGINIA.

BAG-HOLDER.

SPECIFICATION forming part of Letters Patent No. 447,686, dated March 3, 1891.

Application filed June 2, 1890. Serial No. 353,913. (No model.)

To all whom it may concern:

Be it known that I, JOHN M. HOLLADAY, a citizen of the United States, residing at Holladay, in the county of Spotsylvania and State 5 of Virginia, have invented a new and useful Bag-Holder, of which the following is a specification.

This invention relates to bag-holders; and the object thereof is to construct a device of 10 this character almost, if not entirely, of wire, which is capable of being folded into small and compact space, as for storage or transportation, or of being distended to support a bag of any size and at any height above the floor 15 within the limits of the size of the bag-holder.

To this end the invention consists of a device constructed substantially as hereinafter more fully described, and as illustrated in the accompanying drawings, in which—

20 Figure 1 is a perspective view of my improved bag-holder in its open position, showing in dotted lines a bag supported thereby. Fig. 2 is a perspective view of my improved bag-holder in its closed or folded position. 25 Fig. 3 is a side elevation of one of the uprights, showing a slightly-modified shape of its body. Fig. 4 is a side elevation of one of the side braces. Fig. 5 is a detail perspective view 30 of the rear lower corner, showing the brace of the supporting frame-work. Fig. 6 is a plan view showing the manner in which the links are employed to keep the holding-arms in distended position. Fig. 7 is a side elevation of 35 another form of holding-arm. Fig. 8 is a perspective view, considerably enlarged, of the sheet-metal grip employed at the inner end of the holding-arm shown in Fig. 7. Fig. 9 is a plan view, similar to Fig. 6, showing the links 40 as used in connection with the holding-arm illustrated in Fig. 7.

Referring to the said drawings, U U are uprights, of which there are preferably two, as shown in Fig. 1, standing at the rear corners 45 of the device. The lower ends of these uprights may be formed into looped feet s, through which screws or nails may be passed into the floor, and the wire may be thence continued across from one upright to the other 50 to form a bottom brace, as shown at a. Another brace a' preferably connects the two uprights U about where shown, and a top

brace a² connects their upper ends, which ends are provided with hooks h² at the upper corners of the device. The side braces B are 55 duplicates of each other. Each comprises a single wire having an eye i at its upper end, loosely embracing the upright U, thence extending downwardly and provided with a looped foot s at its front end, extending thence 60 rearwardly and about horizontally, as at b, provided with an eye i', that turns freely on the upright U, thence bent at right angles, as at R, and provided with a hook c at its end. Each side brace is thus mounted upon one of 65 the uprights U and can turn thereon.

In its normal position, as shown in Fig. 1, the hook c is engaged over the bottom brace a and holds its side brace at right angles to the supporting frame-work; but when it is 70 desired to fold this device this hook is raised, as shown in Fig. 5, so as to disengage said bottom brace, after which the foot s of the side brace can be turned inwardly against the supporting frame-work.

75 It will be obvious that the two side braces can be turned down one upon the other, and that by making the length of the side braces the same as the width of the frame-work the feet of said braces will not project beyond 80 the opposite uprights when in the folded position shown in Fig. 2. By this means the two uprights and their several braces, comprising the supporting frame-work, are maintained in proper position for use.

85 The holding-arms H are duplicates of each other. Each comprises a single straight bar provided with a hook h at its outer end and with a so-called "grip" g at its inner end. This grip may be composed of the wire which 90 forms the arm H, in which case the wire is bent first into an eye i², standing opposite the inner end of the straight bar H, and then into a V-shaped angle v, standing below the front side of said eye, after which the free end of 95 the wire may be bent into a hook h', or it may be composed of sheet metal, as shown in Figs. 7, 8, and 9, which grip would have the same eye i² and angle v, but in which case the straight bar H would have to be passed 100 through holes o in the free ends of the sheet-metal piece from which the grip was made, and the end of the bar H might be bent into a hook h', as shown in Fig. 7, the bar being

soldered to the grip where it contacts therewith to give the parts greater rigidity. The eye i^2 in the grip fits loosely over the upright U, and the angle v is forced tightly against the front side of said upright when weight is applied to the forward end of the bar H, as will be clearly understood, and the sides of the angle bite the wire and prevent the grip from slipping downwardly thereon. I may, however, provide waves or corrugations in the body of the upright, as shown in Fig. 3, and in this case the angle v need be hardly more than a second eye similar to that lettered i^2 directly above it.

15 L are links, also made of wire, one of which is provided with a hook l and the other with a number of eyes i^3 in its inner end. The outer ends of these links are connected to the two grips g at points in rear of the pivotal points of said grips upon the uprights, as at p. The function of these links when they are used is to lengthen or shorten the distance between the points p, and thereby to throw the holding-arms H inwardly or outwardly to adjust the distance between the hooks h at their forward ends, according to the size of the mouth of the bag, in a manner and for a purpose that will be readily understood. The bag may be engaged at its mouth over the four hooks h and h' , or over the two front hooks h and the two hooks h^2 , if it be desired to hold the rear side of the mouth of the bag a little elevated, as is sometimes desirable. The bag can be then raised and lowered, or the holding-arms H so raised and lowered upon the uprights as to accommodate them to bags of different lengths or depths. When so desired to move either of the holding-arms, it is turned to the position shown in dotted lines in Fig. 1, whereby the angle v is drawn out of engagement with the upright and the grip can be moved freely up or down.

The entire device can be folded, as above described, into very small space, and by disengaging the two links L the holding-arms H can be also folded inwardly, so that the whole bag-holder will occupy a space only the size of the supporting frame-work and of no great thickness.

50 Made, as it is, entirely of wire, or of a small piece of sheet metal, this improved bag-holder can be turned out in a short time with but few tools and at a slight expense; yet it possesses all the advantages and capabilities of a more expensive and complicated device of this character.

What I claim is—

1. In a bag-holder, the combination, with the uprights, a bottom brace connecting them, and holding-arms carried by said upright, of side braces having eyes mounted loosely on the uprights, the bodies of said braces in rear of said eyes being bent at right angles and provided with downwardly-opening hooks adapted to engage said bottom brace, the whole operating substantially as described.
2. In a bag-holder, the supporting frame-

work composed of wire bent into uprights U, connected by an integral bottom brace a, said uprights having hooks h^2 , a central brace a' 7c and a top brace a² at the ends, in combination with braces for holding said frame-work in upright position, and bag-holding arms carried by said uprights, substantially as described.

3. In a bag-holder, the two uprights U, having looped feet s at their lower ends and connected by a bottom brace a, all formed of a single piece of wire, and the side braces B, connected to said uprights and having looped feet s at their front ends, in combination with 80 bag-holding arms, substantially as described.

4. In a bag-holder, the combination, with the uprights and the side braces for holding them in position, of the holding-arms having grips at their inner ends, each grip having 85 an eye near its upper end and an acute angle near its lower end, both embracing the body of the upright, substantially as described.

5. In a bag-holder, the combination, with the uprights having crimped bodies and 90 braces for holding them in position, of the holding-arms having grips at their inner ends embracing said crimped bodies and frictionally supported thereby, substantially as described.

6. In a bag-holder, the combination, with the uprights and the braces for holding them in position, of the wire holding-arms having hooks at their outer ends, and the sheet-metal grips whose bodies are bent at an angle, the 100 upper members thereof being provided with eyes and the lower members with V-shaped angles both embracing said uprights, the inner ends of said holding-arms passing through holes in the ends of said members and being 105 soldered thereto, substantially as described.

7. In a bag-holder, the combination, with the uprights and the braces for holding them in position, of the holding-arms vertically adjustable at their inner ends upon said uprights, each of said arms having hooks at its inner and outer ends, as and for the purpose set forth.

8. In a bag-holder, the combination, with the uprights and the braces for holding them in position, of the holding-arms, the grips secured to the inner ends thereof and vertically adjustable upon said uprights, and the two links extending inwardly from said grips and respectively provided at their inner ends one 120 with a hook and the other with a number of eyes, as and for the purpose set forth.

9. The herein-described bag-holder, the same comprising a rectangular supporting frame-work, side braces pivoted on the uprights thereof at their lower ends, holding-arms pivotally mounted upon said uprights near their upper ends, and means, substantially as set forth, for holding said braces and arms in distended position, as and for the 130 purpose described.

10. The herein-described bag-holder, the same comprising side uprights U, connected by an integral bottom brace a and having

hooks h'' at their upper ends, a central brace a' and a top brace a^2 , side braces B, having eyes pivoted just below said central brace and just above said bottom brace, respectively, of each upright, the lower member b of each side brace having a right-angular arm R, provided with a hook c, holding-arms H, each having a grip vertically adjustable upon said uprights and each provided with hooks $h\ h'$ at its outer and inner ends, respectively, links L, connecting said grips in rear of their pivots on the uprights, and a single hook and

a number of eyes in the meeting ends of said links, the whole constructed and operating substantially as and for the purpose herein- 15 before set forth.

In testimony that I claim the foregoing as my own I have hereto affixed my signature in presence of two witnesses.

JOHN M. HOLLADAY.
